UNITED STATES PATENT OFFICE.

BENJAMIN FURMAN LIVELY, OF LENOIR CITY, TENNESSEE.

BUFFING AND DRAFT GEAR.

1,220,652.

Specification of Letters Patent. Patented Mar. 27, 1917.

Application filed June 17, 1916. Serial No. 104,249.

To all whom it may concern:

Be it known that I, BENJAMIN F. LIVELY, a citizen of the United States, residing at Lenoir City, in the county of Loudon and State of Tennessee, have invented certain new and useful Improvements in Buffing and Draft Gears; and I do hereby declare the following to be a full, clear, and exact description of the invention, such as will 5 enable others skilled in the art to which it appertains to make and use the same.

The present invention relates to buffing and draft gear for railway cars and consists in the arrangements and combinations of 10 parts hereinafter described and particularly set forth in the claims.

The invention has for its purpose to provide a construction of buffing and draft gear employing springs that are adapted to 20 coöperate in series on the initial movement of the draw-bar and then work in parallel on the further movement thereof, to the end of obtaining an increased range of action, together with a graduation of the resistance both for the buffing and draw-bar pull operations.

The invention has for its further purpose to provide a construction of apparatus for the purpose stated which employs the minimum 30 number of parts that are disposed to give uniform distribution of the strains, and in which the elements may be conveniently assembled or disassembled.

The invention is disclosed by way of illustration in the accompanying drawings, wherein Figure 1 is a top plan view of the apparatus with parts in section;

Fig. 2 is a side elevational view thereof with parts in section;

Fig. 3 is a horizontal sectional view thereof showing the springs at the limit of their movement when coöoperating in series; and

Fig. 4 is a similar view showing the springs at the limit of their movement when 45 working in parallel.

Referring to the construction in detail, 1 designates the car structure having mounted thereunder by suitable means a frame 2 of the buffing and draft gear that may be 50 of ordinary construction, substantially as shown, or any suitable form. The draw-bar 3 carrying the usual coupling member 4 is formed with a yoke 5 that is secured to the shank 6 of the draw-bar by the key 7 passing through suitable apertures formed in said shank and the yoke arms respectively.

Said key 7 projects at either end through suitable slots 8 formed in the sides of the frame 2 and is held against displacement by means of the two pins 9 or other suitable devices.

Two pairs of followers 10, 11 and 12, 13 are mounted within the frame 2 and constructed to be embraced by the respective arms of the draw-bar yoke 5 after the manner shown in Fig. 2, and pairs of springs 14 and 15 are mounted between the respective pairs of said followers (see Figs. 1 and 2). Each pair of followers is provided with a second and smaller pair of springs 14^a and 15^a mounted within the larger springs, and said followers and the draw-bar yoke 5 are held in proper working relation within the frame by means of the spacing members or ribs 10^a and 11^a formed on the inner faces of the frame (see Figs. 1 and 3).

The two inner followers 11 and 12 are normally disposed in abutment, as shown, and separated each an appreciable distance from the pair of stops 16 and with which 80 said followers are adapted to engage respectively on the extended movement of the draft bar to be further explained. The end-most followers 10 and 13 are normally held in engagement with a pair of stops 17 and 18 under the expansive action of the springs.

A key 19 is mounted to have sliding movement in the pair of slots 20 in the side walls of the frame and passes through the smaller slots 21 formed in the respective members of the draw-bar yoke 5 and has limited movement therein. Said key 19 also passes between the two inner followers 11 and 12 and is held against displacement by suitable securing rings or collars 22 that are fastened thereto by the pins 23, and said collars 22 are constructed with curved surfaces 24 adjacent the sides of the frame to allow of limited angular movement to the key under the buffing and draw pull strains of the draft gear.

In operation, the initial movement of the draw-bar under buffing imparts a like motion to the follower 10 which, acting on the springs 14 and 14^a, moves the two inner and abutting followers (11 and 12), and these in turn compress the springs 15 and 15^a against the follower 13 that is seated against the stops 18, and throughout this initial operation the springs co-act in series. The extent of this co-operation in series of the springs is determined by the extent of the

space X (see Fig. 1) between the follower 11 and its engaging faces of the stops 16. And on the further movement of the draft bar, *i. e.*, after space X has been taken up, 5 said follower 11 is arrested by the stops 16 and the follower 12 caused to be moved to compress the springs 15 and 15^a due to the engagement of the draw-bar yoke contacting with the key 19 and moving the same 10 against said follower 12, when the two followers 11 and 12 act independently and their respective springs are under compression in parallel. The draw-bar pull will be taken up in a like sequence of operations of the 15 springs, *i. e.*, the two inner followers (11 and 12) will co-act as one element to compress the springs in series on the initial movement of the draw-bar and thereafter work independently to bring the springs under compression in parallel on the continued 20 movement of the draw-bar.

It is obvious that those skilled in the art may vary the details of construction and arrangement of parts without departing from 25 the spirit of my invention, and therefore I do not wish to be limited to such features except as may be required by the claims.

Having thus described my invention, what I claim as new and desire to secure by Letters Patent of the United States is:

1. In a buffing and draft gear, the combination of a frame, a coupler shank movable in the frame, pairs of followers mounted in the frame in tandem, stops on the frame for 35 said followers, a separate element carried by the coupler shank, and springs interposed between said followers respectively, and co-operable in series on the initial buffering movement through the coupler shank and 40 in parallel through the coupler shank and said element on the further buffering movement thereof.
2. In a buffing and draft gear, the combination of a frame, a coupler shank movable in the frame, a yoke member carried by the coupler shank, pairs of followers mounted in the frame in tandem, stops on the frame for said followers, and springs interposed between said followers respectively, and co-operable in series on the initial buffering movement through the coupler shank and in parallel through the coupling shank and said yoke member on the further buffering movement thereof.
3. In a buffing and draft gear, the combination of a frame, a coupler shank movable in the frame, pairs of followers mounted in the frame in tandem, stops on the frame for said followers, a separate element carried by the coupler shank provided with means for engaging both intermediate followers and adapted to move said followers in opposite directions, and springs interposed between said followers respectively, and co-operable in series on the initial buffering move-

ment through the coupler shank and in parallel through the coupler shank and said element; said coupler shank compressing the forward spring and the element compressing the rear spring through the means engaging the rear follower on the further buffering movement thereof.

4. In a buffering and draft gear the combination of a frame, a draw-bar movable in the frame, two pairs of followers mounted in the frame in tandem, stops on the frame for said followers, springs interposed between said pairs of followers respectively, and a pin interposed between the two intermediate followers and having loose engagement with the draw-bar; said followers and springs collectively co-operable in series on the initial movement of the draft bar, and said pin with the stops adapted to bring the springs to work in parallel on further movement of the draw-bar.

5. In a buffering and draft gear the combination of a frame, a draw-bar movable in the frame, two pairs of followers mounted in the frame in tandem, springs interposed between said pairs of followers respectively, stops on the frame normally engaging with the outer followers, stops on the frame intermediate of and spaced from the two inner followers, and a pin associated with said inner followers and having loose engagement with the draw-bar; said springs with the two inner followers co-operable in series on the initial movement of the draw-bar; and said pin with the intermediate stops adapted to bring the springs to work in parallel on the further movement of the draw-bar.

6. In a buffering and draft gear the combination of a frame, a draw-bar movable in the frame and constructed with a yoke having a slot therein, two pairs of followers mounted in tandem on said yoke, springs interposed between said pairs of followers respectively, stops on the frame normally engaging with the two outer followers, stops on the frame intermediate of and spaced from the two inner followers, and a pin slidably mounted on the frame and passing through the yoke slot and between said two inner followers; said springs with the two inner followers co-operable in series on the initial movement of the draw-bar; and said pin with the intermediate stops adapted to bring the springs to work in parallel on the further movement of the draw-bar.

7. In a buffering and draft gear the combination of a frame, a draw-bar movable in the frame and constructed with a yoke having a slot therein, two pairs of followers mounted in tandem in said frame and constructed to be embraced by said yoke, springs interposed between said pairs of followers respectively, stops on the frame normally engaging with the two outer followers, stops

on the frame intermediate of and spaced from the two inner followers, and a pin slidably mounted on the frame and passing through the yoke slot and between said two inner followers; said springs with the two inner followers acting as a single element, coöperable in series on the initial movement of the draw-bar; and said pin and intermediate stops adapted to bring the two inner followers to work independently and cause the springs to be compressed in parallel on the further movement of the draw-bar.

2. In a buffing and draft gear the combination of a frame, a draw-bar movable in the frame and constructed with a yoke having a slot therein, two pairs of followers mounted in tandem in said frame and constructed to be embraced by the yoke, springs interposed between said pairs of followers respectively, stops on the frame normally

engaging with the two outer followers, stops on the frame intermediate of and spaced from the two inner followers; said inner followers being normally in abutment; and a pin slidably mounted on the frame and passing through the yoke slot and through said two inner followers; said springs with the abutting followers coöperable in series on the initial movement of the draw-bar, and said pin and intermediate stops adapted to bring the two inner followers to work independently and cause the springs to be compressed in parallel on the further movement of the draw-bar.

In testimony whereof I affix my signature in the presence of two witnesses.
